UNITED STATES PATENT OFFICE.

CHARLES H. BELLAMY, OF PHILADELPHIA, PENNSYLVANIA.

AUTOMATIC WINDOW-SASH-FASTENING DEVICE.

No. 866,565.

Specification of Letters Patent.

Patented Sept. 17, 1907.

Application filed January 2, 1907. Serial No. 350,413.

To all whom it may concern:

Be it known that I, CHARLES H. BELLAMY, a British subject, and a resident of Philadelphia, in the county of Philadelphia and State of Pennsylvania, have invented certain new and useful Improvements in Automatic Window-Sash-Fastening Devices, of which the following is a full, clear, and exact description.

This improvement relates to sash fastening or locking devices which are attached to and rest upon the meeting rail of the lower sash.

The object of the invention is to provide a sash lock or fastener, simple in construction, automatic in operation, and which can be easily applied by unskilled persons, without detriment to the window, window-sash or casing, this fastener being designed to lock the sashes in any desired position through frictional engagement, admitting at all times of the closing of the upper or the lower sash, or both, but effectually preventing the enlargement of the opening of either or both, unless the fastener be released. These and other objects, as well as the underlying structural features, will become more apparent from the following specification and the appended drawings, and also by reference to the appended claims.

25 In the drawings: Figure 1 is a perspective view of the improved sash fastener applied to the upper face of the meeting rail of the lower sash of a window; Fig. 2 is a longitudinal section on the line 2—2, Fig. 1, the locking wedge being shown as raised out of operative relation 30 to the face of the upper sash; Fig. 3 is a perspective view of the wedge block; Fig. 4 is a perspective view of the casing and the integrally-attached supporting plate; and Fig. 5 is a detail of the operating pin and its retaining devices.

35 Referring now to these drawings, C indicates a casing constructed and arranged to be secured to the meeting rail of the lower sash, for this purpose being formed integral with the basal plate or flange B, which is designed to be fastened flat upon the underlying sash by means 40 of the screws S. Said casing C consists of a steel plate A extending upward from the basal flange B over and away from the face of the upper sash and provided with two cheeks or flanges C¹ and C² formed on the margins of its rear face. The steel plate A, which constitutes the 45 rear wall of the casing, is longitudinally slotted, as at E, the upper end F of this slot being enlarged as shown.

W is the automatic locking member, in the nature of a wedge block slidably mounted on the rear wall of the casing and between the flanges C¹ and C². The face of 50 this block which co-operates with the inner face of the upper sash may be provided with a frictional facing G, or such face may be otherwise adapted to afford a firm grip upon the sash. Extending from front to back of the block W is an aperture K, which may communicate 55 at its front end with a depression L in the face of the block. Within this aperture is rotatively fitted the

operating pin P, this pin extending rearward from the block through the slot E and being suitably provided with a handle portion R. The portion of this pin which is received within the slot is of greater width than thickness, so that, when the pin stands as shown in Fig. 1 it may be received within the body of the slot, whereas, when it is turned as illustrated in Fig. 2, it may only be received within the enlarged portion of the slot. Cotter pins X may serve to retain the pin in the block, 60 one of these pins passing transversely through the extremity of the pin P and being housed within the depression L, while the other may pass through the operating pin outside of the rear wall of the casing.

The operation of the sash fastener is entirely automatic. When it is screwed in place upon the meeting rail of the lower sash, the operating pin P is so turned that its narrowest dimension is normal to the length of the slot E, within the body of which the pin freely slides in this position. Thus the wedge member is free to 70 slide between the two flanges or cheeks C¹ and C² of the casing C, until the forward surface of said wedge comes into frictional engagement with the upper sash. It will be readily seen that any attempt now to lower the upper, or to raise the lower, sash increases the resistance 75 and effectually locks both sashes. When, however, the wedge member is raised by the operating and connecting pin P and the latter is turned, so that it lies transversely of the slot E within the enlarged portion F thereof, the wedge member is held out of frictional 80 engagement with the upper sash and the sashes may be raised or lowered at will.

What is claimed as new is:

1. In an automatic sash fastener, the combination of a casing constructed and arranged to be secured to the 90 meeting rail of a lower sash and to incline therefrom over and away from the face of the other sash, and a wedge block mounted slidably in said casing for engagement with the face of said other sash.

2. In an automatic sash fastener, the combination of a 95 retaining plate constructed and arranged to be secured to the meeting rail of a lower sash and to incline therefrom over and away from the face of the other sash, and a slidably locking member mounted on said plate and arranged to engage with the face of said other sash.

3. In an automatic sash fastener, the combination of a 100 retaining plate constructed and arranged to be secured to the meeting rail of a lower sash and to incline therefrom over and away from the face of the other sash and having longitudinal marginal retaining flanges formed on its inner face, and a slidably locking wedge block mounted on said plate and between said flanges.

4. In an automatic sash fastener, the combination of a 105 casing constructed and arranged to be secured to the meeting rail of a lower sash and having a rear wall disposed to incline therefrom over and away from the face of the other sash, an automatic locking member longitudinally movable on said wall for co-operation with the face of said other sash, and means for preventing separation of the casing and locking member.

110 5. In an automatic sash fastener, the combination of a casing constructed and arranged to be secured to the

meeting rail of a lower sash and having a rear wall disposed to incline therefrom over and away from the face of the other sash, an automatic locking member longitudinally movable on said wall for coöperation with the face 5 of said other sash, and means for operating said locking member.

6. In an automatic sash fastener, the combination of a casing constructed and arranged to be secured to the meeting rail of a lower sash and having its rear wall disposed to incline therefrom over and away from the face of 10 the other sash, an automatic locking member longitudinally movable on said wall for coöperation with the face of said other sash, and means for maintaining said locking member out of engaging relation with reference to said sash-face.

7. In an automatic sash fastener, the combination of a casing constructed and arranged to be secured to the meeting rail of a lower sash and having its rear wall disposed to incline therefrom over and away from the face of 15 the other sash, an automatic locking member longitudinally movable on said wall for coöperation with the face of said other sash, and single means for effecting longitudinal movement of said locking member out of engaging relation with reference to the sash-face and for maintaining 20 it out of such relation.

8. In an automatic sash fastener, the combination of a

casing constructed and arranged to be secured to the meeting rail of a lower sash and having a rear wall disposed to incline therefrom over and away from the face of the other sash and provided with a longitudinal slot enlarged at one portion thereof, an automatic slidable wedge block mounted on said wall, and an operating pin mounted rotatively in said block and extending therefrom through said slot, said pin having its slot-occupying portion of a thickness adapted to be comprehended within 30 the body of the slot and a width similarly related to the enlarged portion of the slot but greater than the width of the body thereof.

9. In an automatic sash fastener, the combination of an apertured plate constructed to be secured flat upon the upper face of the meeting rail of a lower sash, a casing formed integral therewith and having a rear wall disposed to incline therefrom over and away from the face of the other sash, and an automatic locking member longitudinally movable on said wall for coöperation with the 35 face of said other sash.

Signed by me at Philadelphia, Pa., in presence of two subscribing witnesses.

CHARLES H BELLAMY.
